LATCH MECHANISM

William R. Scaife, Milwaukee, and Glenn G. Stoddard, South Milwaukee, Wis., assignors to General Motors Corporation, Detroit, Mich., a corporation of Delaware

Filed Nov. 6, 1961, Ser. No. 150,519

3 Claims. (Cl. 292—5)

This invention relates to latch mechanisms and in particular to an improvement thereof for maintaining the mechanism locked in opened or closed positions.

One form of latch mechanism in the prior art comprises two rods disposed in parallel with respect to each other and mounted within a door. Each of the rods is provided having a rack portion formed thereon. A pinion is interposed in meshing engagement with the rack portions. An actuating handle is fixed with the pinion and serves to rotate the latter so as to obtain axial movement of the rods into or out of engagement with suitable keepers. In addition, the handle is provided with a latch member which rotates into or out of engagement with a third keeper simultaneously with the rods. However, latch mechanisms as described do not provide adequate means for maintaining the mechanism locked in opened or closed positions so that for example once the door is closed and latched the latch mechanism will remain locked until it is desired to open the door.

In accordance with this invention, a latch mechanism of the type including a pair of rods or latch bolts having rack portions formed thereon and driven by a handle actuated pinion interposed in meshing engagement with the rack portions may be maintained locked in opened or closed positions. This is accomplished by using a latch member which is rotatable with the pinion and a lock block which is spring biased for engagement with the latch member. The latch member may be formed having a cam surface interposed between bearing surfaces on the latch member corresponding to latch opened and closed positions. The cam surface cams against the spring biased lock block as the latch member is rotated between latch opened and closed positions. To reduce wear on the lock block, the cam surface may be a surface of a captivated slide element mounted on the latch member. This arrangement is especially adapted for three-point latch mechanisms wherein the latch member may serve as a rotary latch arm with an associated keeper.

A more complete understanding of this invention may be had from the detailed description which follows taken with the accompanying drawings in which:

FIGURE 1 is a front elevational view of one embodiment of the invention;

FIGURE 2 is a side view taken on line 2—2 of FIGURE 1 looking in the direction of the arrows, with parts broken away and in section;

FIGURE 3 is a rear view substantially on line 3—3 of FIGURE 2 looking in the direction of the arrows, with parts broken away and in section;

FIGURE 4 is a sectional view taken on line 4—4 of FIGURE 2 looking in the direction of the arrows;

FIGURE 5 is a sectional view taken on line 5—5 of FIGURE 2 looking in the direction of the arrows;

FIGURE 6 is an exploded perspective view showing the latch arm.

Referring now to the drawings, and more particularly to FIGURES 1, 2 and 3, there is shown an illustrative embodiment of the invention. A U-shaped base 22 is mounted in the interior of a lock casing or door 10 to a front plate 12 by means of screws 24 and 26. A handle base 28 is mounted on the exterior of the door 10 with the front plate 12 by means of screws 24 and 26 and has a circular opening 29 which is coaxially aligned

2

with a circular opening 13 in the front plate 12. An actuating handle 30 provided with a shaft 32 having a rectangular portion 34 and a cylindrical portion 36 is mounted with the handle base 28 such that the cylindrical shaft portion 36 provides a bearing surface with the walls of the circular opening 29. The shaft 32 is axially secured in place with a bowed retaining ring 38 mounted on an annular groove 40 in the shaft's cylindrical portion 36.

The U-shaped base 22 is provided with legs 21 and 23 each having a pair of guide holes extending therethrough co-axially aligned with a pair of guide holes in the other leg and serving to guide a pair of axially movable rods 46 and 48 disposed in parallel with each other, as is shown in FIGURE 3. The rods 46 and 48 are provided with rack portions 47 and 49 formed thereon, respectively. A pinion 42 having a rectangular hole 44 extending therethrough is rigidly mounted on the rectangular portion 34 of the shaft 32 and maintained in meshing engagement with the rack portions 47 and 49. The handle 30 serves to rotate the pinion so as to obtain opposing axial movement of the rods 46 and 48 between extended and withdrawn positions.

In FIGURES 1 and 2 the latch mechanism is shown in its closed position with the rods 46 and 48 respectively extending thru apertures 16 and 18 in the door 10 and co-acting with keepers or striker plates 80 and 82 mounted on a door frame 84. The rods 46 and 48 have tapered ends which cam against cam surfaces provided on the striker plates when the rods are being extended, as is shown in FIGURE 2 in which the rod 46 having a tapered end 45 cams against a cam surface 81 of striker plate 80 so as to pull the door 10 securely against the door frame 84. A latch arm 50 (FIGURE 6) having a canted surface 51 is rigidly fitted with the shaft 32 and rotates therewith between the latch mechanism's closed and opened positions. When the latch arm 50 is rotated toward the closed position the canted surface 51 cams with striker plate 86 mounted on the door frame 84 thus providing a three point latch mechanism for maintaining the door 10 secured with the door frame 84.

A lock block 54 (FIGURE 3) having two guide holes extending therethrough is mounted so as to be in sliding engagement with the rods 46 and 48. The guide holes in the lock block 54 are counter bored providing shoulders 56 and 58 and the guide holes in the leg 23 are counter bored providing shoulders 60 and 62. Spiral springs 64 and 66 are coaxially mounted on the rods 46 and 48, respectively, and seated against the shoulders 58 and 62, and 56 and 60, respectively, thereby spring biasing the lock block 54 in engagement with latch arm 50 rigidly fitted with the shaft 32. A pull back rod 68 is mounted for sliding engagement with a bore hole 70 in the leg 23 and has a threaded end which is screwed into engagement with a threaded hole in the lock block 54 so as to adjust the tension of springs 64 and 66. The rod 68 is held in place with a cotter pin 71.

The latch arm 50 (FIGURE 6) is provided with bearing surfaces 72 and 74 which respectively engage a shoulder 55 of the lock block 54 when the rods 46 and 48 are in their extended and withdrawn positions. A captivated slide block 76 preferably made of nylon is mounted in a co-operating cut-out portion 78 of latch arm 50 and provides a cam surface 77 which cams against the shoulder 55 of the lock block 54 as the latch arm 50 is rotated between the latch mechanism's closed and opened positions. The block 76 is held in place in the cut-out portion 78 with a shoulder 55 of the lock block 54 and a washer 83 fitted with a circular hub portion 57 of the latch arm 50.

An understanding of the operation of the three point latch mechanism may be had from the following descrip-

tion. When the latch mechanism is locked in its closed position, i.e., with latch arm 50 in engagement with the striker plate 86, and the rods 46 and 48 in engagement with striker plates 80 and 82, respectively, the bearing surface 72 is held in engagement with the lock block 54 by virtue of the tension in springs 64 and 66 as shown in FIGURE 3. The latch mechanism will remain locked in its closed position until a sufficient force is applied to the handle 30 to overcome the tension of springs 64 and 66. If the force be such to rotate the shaft 32 in a counterclockwise direction, the cam surface 77 of the captivated slide block 76 will cam against the shoulder 55 of the lock block 54 compressing springs 64 and 65 until the bearing surface 74 engages the shoulder 55 at which time the springs 64 and 65 will flex axially so as to hold the lock block 54 securely against the bearing surface 74. As the shaft 32 is rotated counterclockwise the pinion 42 imparts axial movement to the rods such that the rod 46 is moved toward the left and the rod 48 is moved toward the right (FIGURE 3) and in so doing are withdrawn from engagement with striker plates 82 and 84, respectively. At the same time, the latch arm 50 is also rotated counterclockwise and is disengaged from the striker plate 86. The latch mechanism will remain locked in its opened position until a force is applied to the handle 30 sufficient to overcome the tension of springs 64 and 66.

Although the description of this invention has been given with respect to a particular embodiment, it is not to be construed in a limiting sense. Numerous variations and modifications within the spirit and scope of the invention will now occur to those skilled in the art. For a definition of the invention, reference is made to the appended claims.

We claim:

1. A latch mechanism comprising two rods disposed in parallel and adapted to be mounted within a door, each rod having a rack portion thereon, a pinion interposed in meshing engagement with the rack portions, an actuating handle fixed with the pinion and serving to rotate the pinion so as to obtain opposing axial movement of the rods, the rods being adapted to engage associated striker plates, guide means provided for guiding the rods in parallel with each other as they are axially moved, a latch arm fixed with the handle and rotatable in the same sense as the pinion, the latch arm being adapted to engage a third striker plate, and a spring biased lock block mounted for sliding engagement with the rods and serving to hold the latch arm locked in position.

2. In a latch mechanism having latch opened and closed positions, first and second rods disposed in parallel

and adapted to be mounted within a door, each rod having a rack portion formed thereon, a pinion interposed in meshing engagement with the rack portions, an actuating handle fixed with the pinion and serving to rotate the pinion so as to obtain opposing axial movement of the rods between latch opened and closed positions, first, second and third striker plates adapted to be mounted on a door frame, the first and second rods being in engagement with the first and second striker plates, respectively, when in latch closed position, a latch arm fixed with the handle and adapted to rotate in the same sense as the pinion between latch opened and closed positions, the latch arm being in engagement with the third striker plate when the latch arm is in latch closed position, the latch arm having first and second bearing surfaces, a lock block mounted for sliding engagement with the rods, first and second spiral springs coaxially mounted on the first and second rods, respectively, and serving to spring bias the lock block into locking engagement with the first and second bearing surfaces when the latch arm is in latch opened and closed positions.

3. A latch mechanism comprising rod means including two rods disposed for movement in different directions and adapted to be mounted within a door, each rod having a rack portion thereon, a pinion interposed in meshing engagement with the rack portions, an actuating handle fixed with the pinion and serving to rotate the pinion so as to obtain simultaneous axial movement of the rods, the rods being adapted to engage associated striker plates, means for guiding the rods as they are axially moved, a latch arm fixed with the handle and rotatable in the same sense as the pinion, the latch arm being adapted to engage a third striker plate, and a spring biased lock block mounted for sliding engagement with the rod means and serving to hold the latch arm locked in position.
